(57) **CLAIM**

We claim the ornamental design for a billow air lounge, as shown and described.

DESCRIPTION

FIG. 1 is a perspective view of a first embodiment of the billow air lounge;

FIG. 2 is a right side view of the billow air lounge;

FIG. 3 is a left side view of the billow air lounge;

FIG. 4 is a left side view of the inverted billow air lounge;

FIG. 5 is a right side view of the inverted billow air lounge;

FIG. 6 is a front end view of the billow air lounge;

FIG. 7 is a rear end view of the billow air lounge;

FIG. 8 is a top view of the billow air lounge;

FIG. 9 is a bottom view of the billow air lounge;

FIG. 10 is a further perspective view of a second embodiment of the billow air lounge;

FIG. 11 is a further right side view of the billow air lounge;

FIG. 12 is a further left side view of the billow air lounge;

FIG. 13 is a further left side view of the inverted billow air lounge;

FIG. 14 is a further right side view of the inverted billow air lounge;

FIG. 15 is a further front end view of the billow air lounge;

FIG. 16 is a further rear end view of the billow air lounge;

FIG. 17 is a further top view of the billow air lounge; and,

FIG. 18 is a further bottom view of the billow air lounge.

The grayscale shown in FIGS. 1-18 represents color contrast. The suspended side pocket shown in broken lines in FIGS. 1-9 forms no part of the claimed design, while the color coordinated suspended side pocket shown in solid lines in FIGS. 10-18 represents a claimed design feature.
